GARMENT SLEEVE IRONER

John H. Leef, Minneapolis, Minn.

Application November 3, 1938, Serial No. 238,606

2 Claims. (Cl. 223—73)

My present invention relates to improvements on ironing machines of the type employed for ironing the tubular leg and sleeve portions of garments; and is in the nature of an improvement on or modification of the ironing machines disclosed and claimed in prior Patents 1,937,656 and 2,022,210; the former of which was issued jointly to myself and George H. Leef on December 5, 1933 and the latter of which was issued 10 jointly to myself and said George H. Leef on November 26, 1935. Generally stated, the invention consists of the novel devices, combination of devices and arrangement of parts hereinafter described and defined in the claims.

15 In the said prior patents and in my present improved machine, there is provided a relatively fixed and a relatively movable boot, the movable boot being connected to the fixed boot by an interposed link. In the prior machines the means for moving the movable boot toward and from the fixed boot was a device or devices operating directly on the movable boot but not operating through the link. In these prior arrangements the means for pressing the movable boot toward 20 the fixed boot are to some extent interfered with and prevents the free oscillation of the movable boot on the upper end of the interposed connecting link. In my present machine this objection or feature is eliminated by applying the boot operating action directly to the interposed link, thereby leaving the movable boot perfectly free 25 to oscillate on its pivotal connection with the link and to adapt itself to the outline or divergence of the garment leg, sleeve or other tubular article telescoped over the boots to be ironed thereby.

30 The commercial form of this machine is illustrated in the accompanying drawings wherein like characters indicate like parts throughout the several views.

35 Referring to the drawings:

Fig. 1 is a perspective with some parts broken away and some parts sectional showing the improved machine;

40 Fig. 2 is a section taken through the relative fixed and movable boots on the vertical axes thereof, some of the cooperating parts being broken away;

45 Fig. 3 is a perspective showing in detail an actuating foot pedal and a portion of the machine frame; and

50 Fig. 4 is a section taken approximately on the line 4—4 of Fig. 3.

Mounted on a common supporting table which 55 consists of a top 7 and a frame-like leg structure 8, are pairs of cooperating hollow pressing boots.

Each pair of boots involves a fixed boot 9 and a movable boot 10. A leaf-like link 11 is, at its lower end, pivotally connected at 12 to the base or lower portion of the fixed boot 9, and at its upper end is connected at 13 to the intermediate 5 portion of the movable boot 10. The boots 9 and 10 on their abutting or adjacent faces are recessed respectively at 9a and 10a to clear the link 11 when the cooperating boots are forced together.

10 These hollow boots will be supplied with steam through suitable delivery pipes 14 and exhaust pipes 15, the arrangement of which need not be considered here further than to state that the connections to and from the movable boot will be 15 flexible or such as not to interfere with the free movement of said movable boot.

15 In accordance with this invention the link 11 is provided with a depending and extended portion, which together with the link, forms a sort 20 of bell-crank structure pivotally mounted at its elbow. This extension, as shown, is formed by a flat bar 16 and a projecting arm 17. The bar 16 is rigidly secured at its upper end to the lower part of the link 11 by riveting, soldering or otherwise; and at its lower end said bar is rigidly secured to the end of the arm 17 by welding, riveting or otherwise.

25 The extended ends of the arm 17 are connected by connecting rods or links 18 to the arms of a 30 foot pedal 19 that is pivoted on a rod 20 extended between and secured to the lower portions of the sides of the frame 8. The lower ends of the connecting rods are provided with forked heads that embrace the ends of the arms of the pedal 19 35 and are connected thereto by pins 21 that work in longitudinal slots 22 in the arms of pedal 19, thereby affording a slip connection, the importance of which will presently be noted. The upper ends of the connecting rods 18 are provided 40 with forked heads that embrace the ends of the arms 17 and are connected thereto by pivot pins 23 which, as shown, are insertable through any one of several pin holes formed in said arms.

45 Pivoted to the arms of the pedal 19 at 24 is a lock dog 25 provided at its upper end with a foot plate 26 and at its lower end with a bevelled lock lug 27 that is engageable with a lock detent or flange 28 on a fixed portion of the frame 8. The foot pedal 19 has a foot plate 29 that 50 is notched at 30 to allow the foot plate 26 of the lock dog to work therein. This foot plate 26 is narrower than the foot plate 29 so that it can be engaged and disengaged by the foot on the plate 29 simply by lateral movement of the foot. 55

When the foot on the plate 29 is pressed downward, the movable boots will be pressed toward and against the cooperating fixed boots. In performing this operation the pivot pins 21 will slip 5 downward and backward in the slots 22 as far as they will go, thus causing the two movable boots to be pressed closely against the cooperating boots. When this operation is performed while the lock dog 25 is released, the latter will engage the 10 detent 28 and lock the boots together as indicated.

To unlock the movable boots for separation from the cooperating fixed boots, it is only necessary to press the foot on the plate 26 of the lock dog, thereby releasing said dog from the 15 detent 28. When this is done, the movable boots, under the action of gravity, will move away from the cooperating fixed boots.

The extent that the movable boots thus move away from the fixed boots will depend on the size and form of the 20 garment leg or the like that is telescoped over the cooperating boots; and in this action it is important to note that the movable boots pivot freely on the pivots 13 so as to adapt themselves to the shape and divergence of the article being 25 ironed.

It is further important to note that the two movable boots are capable not only of independent oscillatory movements on the pivots 13, but are capable of different degrees of movement away 30 from the cooperating fixed boots due to the fact that when one of the fixed boots has engaged and adapted itself to the particular garment leg or the like, the pivot pin 21, at the lower end of the connecting rod 18 can slip outwardly and upwardly in the slot 22. This permits the movement 35 of the one movable boot away from its cooperating fixed boot to be interrupted before the other movable boot has completed its movement away from its cooperating fixed boot. The movement 40 of the movable boots away from the fixed boots under the action of gravity when the lock dog is released is, of course, due to the location of pivots 12 forward of the centers of gravity of the 45 movable boots.

Adjustments of the pivot pins 23 at the upper ends of the connecting rods 18 not only permits variation in the throw of the arms 17 but permits independent adjustments of the two arms and,

hence, of the movements of the movable boots away from the fixed boots.

From the foregoing it will be understood that the device described is capable of modifications within the scope of the invention herein disclosed and claimed. 5

What I claim is:

1. In a device of the kind described, a supporting frame, a pair of fixed boots mounted on said frame, relatively movable boots cooperating with said fixed boots, links independently pivoted to said fixed boots at the lower ends and independently pivoted to said movable boots at their upper ends, said links having laterally projecting arms, a foot pedal pivotally mounted on said supporting frame, and connecting rods independently connecting said foot pedal to the arms of said links, and in which structure the lower ends of said connecting rods are independently connected to said foot pedal by slot and pin slip acting connections that operate positively to force the respective movable boots toward the fixed boots but slip to permit differential movements of the two movable boots away from their cooperating fixed boots. 25

2. In a device of the kind described, a supporting frame, a pair of fixed boots mounted on said frame, relatively movable boots cooperating with said fixed boots, links independently pivoted to said fixed boots at their lower ends and independently pivoted to said movable boots at their upper ends, said links having laterally projecting arms, a foot pedal pivotally mounted on said supporting frame, and push linkage independently connecting said foot pedal to the arms of said pivoted links, said push linkage involving independent connecting rods each pivotally anchored to and interlocked with the common foot pedal at its lower end and pivotally anchored to and interlocked with an opposite of said arms at its upper 40 end, the linkage between said foot pedal and each of said arms involving limited slack motion connections, whereby the movable boots will be simultaneously moved toward their respective fixed boots under lifting pressure exerted on the pedal but will be free for limited differential movement away from their respective fixed boots when the pedal is relieved of lifting pressure. 45

JOHN H. LEEF.
